UNITED STATES PATENT OFFICE.

ALFRED B. LEMON, OF PROVIDENCE, RHODE ISLAND.

DESIGN FOR A CHARM.

Application filed February 11, 1922. Serial No. 657. Term of patent 3½ years.

To all whom it may concern:

Be it known that I, ALFRED B. LEMON, a citizen of the United States, residing in the city and county of Providence, and State of Rhode Island, have invented a new, original, and ornamental Design for a Charm, of which the following is a specification, reference being had to the accompanying drawing, forming a part thereof.

The figure is a face view of a charm, illustrating my new design.

I claim:

The ornamental design for a charm, as shown.

ALFRED B. LEMON.
